UNITED STATES PATENT OFFICE.

JULIUS T. SENG, OF CHICAGO, ILLINOIS, ASSIGNOR TO THE SENG COMPANY,
OF SAME PLACE.

LID-OPERATING MECHANISM FOR BOX-COUCHES.

SPECIFICATION forming part of Letters Patent No. 644,337, dated February 27, 1900.

Application filed January 11, 1900. Serial No. 1,121. (No model.)

To all whom it may concern:

Be it known that I, JULIUS T. SENG, a citizen of the United States, residing at Chicago, in the county of Cook and State of Illinois, 5 have invented certain new and useful Improvements in Lid-Operating Mechanisms for Box-Couches; and I do hereby declare the following to be a full, clear, and exact description of the invention, such as will enable 10 others skilled in the art to which it appertains to make and use the same.

This invention relates to improvements in box-couches, and particularly to the mechanism employed for aiding in the raising of the 15 seats or lids thereof. I am well aware that various mechanisms of more or less practicability for this purpose have been devised and patented, and among them certain mechanisms designed to accomplish this object while 20 the couch is located against a wall, and it is to this latter style, wherein the necessity of withdrawing the couch from the wall to enable the rear edge of the lid to escape the same in its opening movement, that my present invention pertains.

The objects of my invention are to reduce to a minimum and simplify the number of parts necessarily employed and so organize, connect, and arrange these parts as to facilitate 30 their application to the couch and render the whole mechanism efficient, cheap, and highly practicable.

Other objects and advantages of my invention will appear in the following description, 35 and the novel features of the invention will be particularized in the claims.

Referring to the drawings, Figure 1 is a transverse sectional view of a box-couch provided with my invention, the couch being 40 shown as closed. Fig. 2 is a similar view, the lid being shown in elevation and the parts in the position they occupy after an initial raising of the lid. Fig. 3 is a view similar to Fig. 2, the parts being in the position they 45 occupy when the lid is raised. Fig. 4 is partial section and side elevation of a box-couch, the lid being shown closed and the couch provided with a slightly-modified construction of opening mechanism. Fig. 5 is a vertical sectional view through the wall of the couch, the guide-plate, and the securing-plate. 50

Fig. 6 is a detail in perspective of the securing-plate. Fig. 7 is a detail in elevation of the preferred form of slotted guide-plate employed, and Fig. 8 is a similar view of a modified form of guide-plate hereinafter referred to.

Similar numerals of reference indicate similar parts in all the figures of the drawings.

In each of the figures of the drawings where in the couch is shown, 1 designates the lower receptacle or body portion, and 2 the lid or upholstered seat, which latter in the old form of box-couch was hinged at its rear edge to the adjacent back edge of the receptacle portion, but which in the improved form to which this invention relates is independent of the same in that hinges, properly speaking, are entirely omitted and in their stead are employed what I term "opening mechanisms." 70

In practicing my invention I secure by screws, bolts, or other fastenings to the opposite end walls of the receptacle portion 1 longitudinally-slotted guide-plates 3, which are preferably stamped from heavy sheet 75 metal. These plates 3 may be applied to the said end walls in an inclined position, as I have shown, or if applied in a horizontal manner the same result could be secured by forming the slots on an incline with relation 80 to the plates. I shall therefore for the purpose in view term them "guide-plates having inclined slots 4." The guide-plates 3 may be each provided with a simple straight inclined slot 4, as illustrated in Figs. 4 and 8, or, as 85 preferred, the rear end of this slot may be provided with a somewhat-abrupt depression or branch 5, as shown in Figs. 1, 2, 3, and 7. In either instance the upper longitudinal half of this plate is preferably offset from the lower 90 half, as best shown in Fig. 5. These guide-plates are located near the rear upper corner of the opposite end walls of the receptacle portion of the couch preferably, but may be otherwise located, if desired—as, for instance, 95 along the upper edge. However, the location in which I have shown them I consider the most practicable and certainly so when employed in connection with the hereinafter-described mechanism.

Any suitable device may be employed for aiding in the raising of the lid 2—that is, a

lever, as 6, one for each end, or any of the well-known systems of levers now in use or hereafter devised. In the present instance, however, I prefer to employ a simple lever of 5 straight design or what would, more properly speaking, be called a "link." This link, then, is, as herein shown, pivotally connected at its lower end to a suitable bracket or fastening 7 of any desired design, securely attached 10 to the end wall of the receptacle portion of the couch, and at its upper end the said link is pivotally attached to the under side of the couch-lid 2. In the present instance I have 15 illustrated one simple way of pivotally securing the upper end of the lever to the lid—namely, by way of an angular securing-plate 8, the same being shown in its preferred form in detail in Fig. 6. It is obvious, however, that any other means may be employed for 20 connecting the upper ends of these links or levers 6 to the under side of the couch-lid or at any other point desired and found necessary.

The angular securing-plate 8 is believed to 25 facilitate the application of the device, and hence it is preferred to employ the same. This plate is illustrated in its preferred form in Fig. 6, and as therein seen it comprises an upper securing-flange 9, perforated at intervals for the reception of bolts or screws, as indicated at 10, and it also comprises a depending portion 11, to the front corner of which is pivoted, as at 12, the upper end of the link or lever 6. Back of and below this 35 point the plate is reduced in width and offset to form a leg 13, the same by reason of its offset escaping the adjacent guide-plate 3. At the lower end of the leg there may be formed an inwardly or horizontally extending lug 14, provided with a perforation, and above this lug there may extend inwardly from the lug a headed stud 15, formed on or attached to the leg in any desired manner whatsoever. The neck of the stud rides in 40 the slot 4, while the head thereof, if employed, engages the inner edges of the said slot.

A fastener 16 is secured to each end wall of the receptacle portion 1 of the couch, and extending from each of the said fasteners to the 45 perforated lug 14 of the angular securing-plate at that side of the couch is a contracting spring 17. It will be understood that the relative arrangement of the spring with the remaining parts to be actuated thereby may be varied at will, and I have illustrated merely the preferred form. As I have indicated by dotted lines in Fig. 4, the link 6 may be extended below the pivot-point 7 and the spring be connected thereto and extend from thence either to the rear wall of the couch-receptacle or to the angular securing-plate, all as will be obvious. Moreover, I do not confine myself to the employment of the securing-plate 8, for, 55 as before stated, the upper end of the link or lever 6 may be pivoted directly to the under side of the couch-lid and an arm, lug, or other

equivalent of the leg 11 may be employed, the same being wholly independent of the pivotal connection between the couch-lid and the link 70 or lever 6. The office of the spring is of course to aid in the raising of the couch-lid, and it may be given any relative position with the remaining mechanism to accomplish this function. It may be so light in its tension as 75 to be incapable of elevating the lid, or it may be so relatively arranged with the lever 6 as, although under tension when the lid is closed, yet to be practically powerless until the lid is given an initial raise, all as is now commonly 80 practiced in the art. The operation, however, is practically the same. The operator by first giving an initial raise to the lid starts the same, when the tension of the spring begins to be felt and either continues or completes 85 the operation or aids in the same, as the case may be. The rear edge of the lid slides forward a sufficient distance to clear the adjacent wall and at the same time partially turns on the studs 15, which, it will be understood, 90 move in the guide-slots 4. By forming the slots 4 at more of an angle at their rear ends, as at 5, the lid is moved more suddenly upward—in fact, is given an upward movement the instant the lid begins to move the slightest and 95 before any revolving motion of the lid begins. It is for this reason that I employ this form of slot in practice, the straight slot having a tendency to permit of the upholstering of the lid to contact to some extent with the wall. 100

Having described my invention, what I claim is—

1. The combination with a box-couch, of guide-plates mounted on the receptacle portion thereof near its rear wall, and provided 105 with slots disposed at an inclination to the couch, and means located between and adapted for slidably and rotatably connecting the lid near its rear end with the said guide-plates, and spring-actuated mechanisms for aiding in sliding and partially rotating said lid.

2. The combination with a box-couch, of guide-plates mounted on the receptacle portion of the couch and provided with inclined slots, the rear ends of the slots of the said 115 guide-plates being somewhat abruptly depressed with relation to the remaining portions of the slots, means located between and adapted for slidably and rotatably connecting the lid near its rear edge with the said slots, 120 and spring-actuated mechanisms for aiding in sliding and partially rotating said lid.

3. The combination with a box-couch, of guide-plates arranged upon the end walls of the receptacle portion and having slots disposed at an inclination, means for slidably and rotatably connecting the said lid with the aforesaid slots of the plates, and spring-actuated mechanisms for aiding in sliding and partially rotating said lid.

4. The combination with a box-couch, of opposite inclined plates applied to the inner surfaces of the end walls of the receptacle portion of the couch near the rear upper cor-

ner thereof and provided with slots arranged at an inclination with relation to the couch, of means depending from the lid and slidably and rotatably connecting the same with the 5 slots of the plates, and spring-actuated mechanisms for aiding in sliding and partially rotating said lid.

5. The combination with a box-couch, of opposite inclined guide-plates applied to the 10 inner surfaces of the end walls of the receptacle portion of the couch near the rear upper corner thereof, and provided with slots arranged at an inclination, the rear ends of which slots are suddenly depressed or ar- 15 ranged at an angle to their remaining portions, of means depending from the lid and slidably and rotatably connecting the same with the aforesaid slots of the plates, and spring-actuated mechanisms for aiding in 20 sliding and partially rotating said lid.

6. The combination with a box-couch, of oppositely-located plates having inclined guide-slots secured to the inner surfaces of the end walls of the receptacle portion of the 25 couch, a plate or bracket depending from each end of the couch-lid and having a lug engaging slidably and rotatably in the slot of the adjacent guide-plate, and spring-actuated mechanisms for aiding in sliding and par- 30 tially rotating said lid.

7. The combination with a box-couch, of opposite guide-plates secured to the inner surfaces of the end walls of the receptacle portion of the couch, said plates having inclined 35 guide-slots, opposite angular plates or brackets depending from the under side of the couch-lid and terminating in legs offset to

avoid said plates and having headed lugs en- gaging said slots of the guide-plates, and spring-actuated mechanisms for aiding in 40 sliding and partially rotating the said lid.

8. The combination with a box-couch, of opposite guide-plates having inclined slots and secured to the inner surfaces of the end walls of the receptacle portion of the couch, 45 securing-plates depending from the under side of the couch-lid and terminating in de- pending legs provided with studs engaging the slots, lid sliding and rotating devices ar- ranged in advance of the same, and coiled 50 springs connected to the depending legs and to a point within the couch-body for aiding in sliding and rotating the said lid.

9. The combination with a box-couch, of opposite guide-plates having inclined slots 55 and secured to the inner surfaces of the op- posite end walls of the receptacle portion of the couch, a pair of angular securing-plates located on the under side of the couch-lid and provided with headed studs engaging 60 the said slots and below the same provided with laterally-disposed lugs having perfora- tions, coiled springs connected to the said perforations and to fixed points within the couch-body, and links connected pivotally to 65 the end walls of the receptacle portion and similarly to the under side of the said secur- ing-plates.

In testimony whereof I have affixed my sig- nature in the presence of two witnesses.
